ICE-CREAM CONE OR THE LIKE

Attilio Agostino Guido Marcantonio, London,
England, assignor to Embisco Limited

Application February 15, 1952, Serial No. 18,538
In Great Britain August 21, 1951

Term of patent 14 years

(Cl. D3—1)

To all whom it may concern:

Be it known that I, Attilio Agostino Guido Marcantonio, subject of the King of Great Britain and Ireland, residing at London, England, have invented a new, original, and ornamental Design for an Ice Cream Cone or the like, of which the following is a specification, reference being had to the accompanying drawing, forming part thereof.

Figure 1 is a front elevational view of an ice cream cone showing my new design;

Figure 2 is a side elevational view thereof;

Figure 3 is a sectional view taken on the line 3—3 of Figure 2;

Figure 4 is a top plan view of the ice cream cone shown in Figure 1; and

Figure 5 is a perspective view thereof looking toward the rear.

I claim:

The ornamental design for an ice cream cone or the like, substantially as shown.

ATTILIO AGOSTINO GUIDO MARCANTONIO.
